UNITED STATES PATENT OFFICE

OSCAR S. FIELD, OF ALBANY, NEW YORK, ASSIGNOR TO GENERAL RAILWAY SIGNAL COMPANY, OF ROCHESTER, NEW YORK

RELAY

Application filed July 27, 1926. Serial No. 126,914.

This invention relates to improvements in direct current relays, more particularly that type of relay used in connection with railroad signalling.

One of the objects of the invention is to provide a relay that has a very high relative efficiency. A further object is to provide a relay which is dependable in its operation, and which will not materially change its operating characteristics over a fixed working period. A further object is to provide means whereby the relay can be readily assembled and adjusted and, further, whereby the contact tension airgap and other vital operating functions may be readily adjusted, to maintain a uniform operating characteristic in all relays manufactured of the same type.

With these objects in view and further objects as may appear from the following specification and appended claims, I will now proceed to describe one embodiment of my invention, together with its means of operation.

Figure 1 is a cross section through the relay from front to rear. Figure 2 is a plan view 25 of the relay in the inverted position and with its cover glass removed. Figures 3, 4 and 5 are upper and lower plan views and a cross section of the finger structure employed in the relay. Figures 6, 7 and 8 are side elevation, 30 transverse section, and inverted plan view respectively, of the front contact carrying member.

Broadly speaking, the delay comprises an assembly of 3 unitary constructions, the first 35 consisting of the magnetic system with its mounting plate, armature and contact fingers, the second comprising the insulating top of the relay equipped with contacts adapted to co-act with the before mentioned contact 40 fingers, and the third unit comprises the cover glass adapted to encase the moving parts and keep them free from dust and moisture.

The first structure comprises a metallic base plate 1 in which are suitably mounted Norway 45 iron cores 2 and 3 respectively. These cores are provided with enlarged pole shoes 4 and 5 which serve the purpose of increasing the area of the operating airgap 6 in addition to providing means for mounting the cores 2 and 50 3 in the base plate 1 by means of screws 7 as

indicated in Figure 2, which are adapted to pass through the base platen into holes tapped into the pole shoes. The cores 2 and 3 are provided with operating windings 8 and, further, provided with cross connecting yokes 9 and 10, rigidly clamped to flattened surfaces 11 and 12 formed on the core extremities by means of suitable bolts and nuts 13. It is, of course, understood that the connecting yokes 9 and 10 are made of suitable flux conducting material such as Norway iron.

In order to provide terminals for the coils 8, I propose to furnish a supporting plate 14 which is clamped by the bolts and nuts 13 to the core assembly and is adapted to carry an insulating block 15, supported thereon by means of screws and nuts 16, the insulating block 15 in its turn supporting binding posts 17 adapted to be connected by means of leads 18 to the coils 8.

On the under side of base plate 1 there is formed downward extensions 19 and 20 respectively. These extensions are provided with supporting studs 21, the purpose of which is to adjustably support a bearing plate 22, this plate being arranged to have perforations in extended ears 23 and 24 adapted to slide over the studs 21. Adjusting nuts 25 are provided on the studs 21 whereby the bearing plate 22 may be adjusted up and down in a vertical plane, thereby forming a means of adjustment for the airgap 6. In operative relation to pole shoes 4 and 5 and adapted to co-act therewith an armature 26 of suitable material such as Norway iron is provided. This armature has riveted thereto at 27 and 28 respectively trunnion carrying arms 29 and 30. The arm 29 is provided with a trunnion member 31, adapted to be adjusted horizontally therein and to co-act with bearing member 32 on bearing plate 22. This trunnion member 31, after it has been set horizontally in the proper position, is drilled and permanently riveted in place by means of rivet 33. The arm 30 is provided with a trunnion member 34, having an enlarged head 35 which is adapted to engage the inner surfaces of the arm 30. This trunnion member is provided with a locking groove 36 through which a locking screw 37 is passed, said screw 100

being adapted to screw into the trunnion arm 30. The trunnion arm 30 is further provided with a slot 38 whereby upon the tightening of screw 37, the trunnion member 34 is rigidly 5 clamped in place. The trunnion member 34 is adapted to co-act with the bearing member 39, carried by bearing plate 22.

From this construction it will be seen that I have provided means for pivotally supporting the armature 26 in such a way that it may be adjusted for horizontal end play in its pivots and then rigidly set, after which the armature may be removed from its bearings by removing the trunnion 34 and again replaced without in any way interfering with the predetermined fixed end play adjustment. I have further provided means whereby the armature may be readily adjusted in a vertical plane in relation to its pole shoes 4 15 and 5 respectively.

The armature 26 is provided with stop pins 40 which are adapted to maintain a minimum airgap between the pole shoes and armature, in order to prevent what is known as "freezing", due to retention of residual magnetism 25 in the iron structure.

On the underside of armature 26 insulating studs 41 are provided, these studs being made of insulating material equipped with metallic 30 threaded inserts 42 and 43 in a manner well known in the art. These studs are adapted to carry the contact finger assemblies 44.

In connection with the finger assembly 44, it is the purpose to provide a contact finger 35 which may be adjusted vertically relative to the armature in order to compensate for varying airgap adjustments and irregularities in manufacture and also to provide a contact element in which we may readily adjust the 40 contact pressure and also readily remove the contact elements. In order to accomplish these purposes, I have provided a finger which has a main channel section 45, the rear end of which is reduced to a simple flat section as 45 shown at 46 in Figure 4. The channel is provided with an adjusting nut 47 which passes through an aperture 48 in the channel structure 45 and through a washer 49 being spun over on the upper side as shown at 50, whereby the nut is rigidly connected to the channel member 45 so far as vertical play 50 is concerned but is free to rotate therein. The flat section 46 of the channel member is provided with an opening 51 through which 55 the stud 42 of the rear insulator 41 passes and it is rigidly clamped in place by means of a clamping nut 52. The adjusting nut 47 is adapted to engage the front stud 42, whereby upon rotation of the nut the channel member 45 will be hinged about edge 53 and will be caused to move up or down in accordance with the direction of rotation of the adjusting nut 47. A locking plate 54 is provided 60 and is adapted to pass under the nuts 52 and 65 47 whereby, after the finger assembly has been

properly adjusted, the edges of the locking plate may be turned up about the hexagonal sides of the nuts as indicated at 55, thereby locking them against rotation.

It will be seen that this combination comprises a means for adjustably mounting the main element of the finger assembly on the armature whereby it may be adjusted to its proper position and then rigidly locked in place. The front end of the channel section 70 45 is provided with a slot 56 and is further provided with a rear contact spring 57 equipped with a silver contact point 58 and riveted to the channel member 45 as shown at 75 59. The contact spring is provided with a narrow section 60 adapted to pass through the slot 56 and is bent over so as to engage with the channel member 45 as indicated at 80 61, thereby retaining a definite amount of trapped pressure in the spring 57. In order 85 to adjust the trapped pressure all that is necessary is to spring the front end 62 of spring 57 forward so that the spring becomes disengaged from the channel member 45, thereby allowing any desirable set to be put 90 in the spring 57 after which it is again allowed to snap back into place.

When the contact 58 co-acts with its complementary contact member the spring 57 is compressed until the shoulders 63 engages 95 with the sides of the slot 56 in channel member 45, thereby limiting the amount of compression on spring 57.

Behind the rivets 59 in channel member 45, a combination clamping screw and pivot point 100 64 is provided and is adapted to pass through the channel member 45 and be held in place by means of the nut 65, said nut being held from rotation by means of indentations 66 formed in the channel member 45. Member 64 performs two functions. The first function is to provide a pivot over which the contact carrying element 67 may rock, and the second is to provide means for clamping the eyelet 68 of pigtail 69 rigidly to the channel member 110 45, whereby good electrical contact is maintained.

The upper contact carrying member 67 is provided with an indentation 70 arranged to co-act with the pivot 64. It is provided at its front end with a downwardly extending lip 71 adapted to pass thru slot 56 of channel member 45. The lip 71 is larger at its lower end 72 so that it will engage the sides of the slot 56 on the under side of the member 120 45 when the contact member 67 tends to rise in a vertical direction, thereby limiting this movement but leaving the element free to be depressed. On the opposite side of the contact carrying member 67 a spring stud 73 is 125 provided adapted to pass through aperture 74 in the member 67 and is equipped with an adjusting nut 75 and a locking nut 76, the operation of which will be described hereafter.

The channel member 45 is provided with a recess 77 on the under side thereof for the purpose of centralizing the spring 78 which maintains the spring stud 73 under tension. It will be seen that if the spring stud 73 is rotated it will either tighten up on the pressure of spring 78 or reduce the same, according to the direction of rotation, thereby varying the tension through nut 75 on the rear end of front contact carrying member 67. In this way it is obvious that the tension necessary to depress the front end of member 67 may be varied. In order to adequately lock the stud 73 from rotation when adjustments are not being made, upwardly extending ears 79 are provided on member 67. The stud 73 is provided with a nut 76 which is pinned to the stud by means of a pin 80, whereby the nut 76 must rotate in unison with the stud 73. In order to rotate the stud 73 therefore, it is necessary to compress the spring 78 so that the locking nut 76 may extend above the ears 79. The stud is then free to be rotated in either direction but upon release of the pressure the nut will drop down between the ears 79, thereby rigidly locking the stud from further rotation.

I have shown on the front end of the contact carrying member 67 a contact element 83 which is known in the art as a gauze contact. This comprises a spring supporting frame 81 riveted to member 67 at 82 as shown. Mounted in this frame is a silver gauze contact 83, said contact being equipped with end supporting pieces 84 and 85 adapted to engage with hook members 87 and 86 respectively on the spring supporting member 81. From this construction it is seen that this member may be readily removed by squeezing the spring carrying member 81 together, thereby allowing the gauze element to be lifted out. This construction is not new and is well known in the prior art.

In the present embodiment, the gauze element is equipped with an extension 88 adapted to carry a pigtail 69 which is connected to member 45 as previously described. By this construction I have provided means whereby the spring element 81 is not called upon to carry current from the gauze contact 83 to the finger structure proper. The practice of using this member as a current carrying element has been found in practice to be detrimental to the proper functioning of the contact owing to variable resistance conditions in the connection between the gauze and the spring element. In some cases this has caused failures due to excessive heat generated at this point which draws the temper of the spring supporting member.

I have now fully described the various elements incorporated in section one of the assembly.

Section two consists of a top 89 made of suitable insulated material such as bakelite.

This top has formed therethrough an opening 90 surrounding which is a raised part 91 on which the mounting plate 1 is adapted to rest, being rigidly held in place by means of screws 93. When the mounting plate 1 is assembled in this position, the pole shoes and armature structure extend downwardly through the top 89 as shown in Figure 1. The top is further provided with a series of recesses adapted to carry contact carrying stirrups 94 with their co-acting binding posts 95 and back contact elements 96, said contact elements being carried in such a position as to be in operative relation with the back contact 58 of the contact finger 44. When the relay is de-energized the contacts 58 rest on the co-acting contacts 96 and the contacts act as back stops to limit the dropping-away movement of the armature 26. It will be seen that by bending the stirrups 94 up or down at point 97, the dropping-away movement of the armature may be readily adjusted.

To co-act with the gauze contact elements 83 front contacts 98, more particularly illustrated in Figures 6 to 8 inclusive, are provided. These contacts are usually made of carbon or some other suitable nonfusing material. It is desirable in connection with these contacts to mount them in the top 89 in such a manner that they cannot be disturbed from the outside of the relay. In order to accomplish this, I have provided a special binding post 99 equipped with a square head 100 and adapted to be screwed through a nut 101 which is set in a hexagonal recess 102 in the top 89 whereby the nut 101 cannot turn. A clamping element 103 is provided which is adapted to pass over the shank of contact stud 99 and rest on the upper side of the square head 100 as shown at 104. This member is provided with an extension 105 which projects beyond the edge of the square head 100. A screw 106 is passed through the member 103 and threaded into the square head 100 and adapted to project through as shown at 107. This screw rigidly locks member 103 to the head 100 and provides means for removably clamping the carbon block 98 as will hereafter be described. The member 103 is further provided with an extending ear 108 which is adapted to engage in a recess 109 formed in the top 89. It will be seen that after the contact combination has been screwed in place and the ear 108 is depressed into the recess 109 as clearly shown in Figures 7 and 8, that the post will be rigidly locked from rotation and it will be impossible to remove it from the top 89 unless the ear 108 is raised from the slot 109. Member 103 has a downwardly extending part 110 which is adapted to engage the contact block 98 which is suitably beveled in order to facilitate the clamping action.

A co-acting plate 111 is provided which

has a clamping part 112 complementary to the part 110 and is further provided with an opening at 113 through which the end 107 of screw 106 passes and is adapted to engage the end 105 of member 103. It will be seen that when this member is clamped in place by means of a nut 114 that the element 112 will rigidly clamp the carbon block 98 between members 112 and 110. The carbon 98 is provided with a hole 115 therethrough and an ear 116 is formed on member 112 and adapted to pass into the hole 115. The purpose of this is to form a safety feature to prevent the carbon block 98 from dropping should it become loose.

The relation of the co-acting contacts and the contacts on the contact finger are clearly shown in Figure 1 and they are so adjusted that when the relay is de-energized the back contacts will close and the front contacts open and when the relay is energized the front contacts will close and the back contacts open in such a manner as to give a definite amount of compression to the springs 78. In order to obtain electrical connection to the contact fingers suitable pigtails 117 are provided and are arranged to connect to contact stirrups 118 and 119 respectively which are equipped with binding posts 120. The top 89 is further provided with a groove 121 in which a suitable gasket, preferably of felt, 122 is provided. This gasket is for the purpose of co-acting with the third element of the structure, that is the enclosing case 123. This case is preferably moulded in transparent glass so that the operation of the relay may be readily inspected at any time. The glass is provided with suitable legs 124 which have recesses 125 in which supporting springs 126 may be cemented when the relay is used as a shelf type relay. The spring 126 is for the purpose of absorbing undue shock and vibration.

The glass cover 123 is provided with a recess 127 having an aperture 128 through which passes a clamping stud 129 suitably supported from top 89. The glass is held in place by means of the clamping nut 130 being suitably protected against crushing effects by a rubber washer 131. Should it be desirable to mount the relay upon the wall, wall hangers 132 may be provided being made of a resilient material and rigidly attached to mounting plate 1. In this manner the relay may be rigidly mounted to the wall and the greatest element of weight will be directly carried through the contact supporting plate 1 rather than through the insulating top 89, thereby relieving this top of any undue strains in service.

While I have described and illustrated one form of my invention, it is to be understood that I may depart from many of the details of construction without departing from the spirit of the invention.

What I claim is:

1. In combination in a relay, a supporting top, an electromagnet and co-acting armature carried by said top, contact fingers on said armature, front and back contacts carried by said top in operative relation to said contact fingers, adjusting means whereby said contact fingers may be individually adjusted on said armature and locking means for said adjusting means.

2. In combination in a relay, a supporting top, an electromagnet carried by said top, a co-acting armature, removably supported by said top, contact fingers on said armature, front and back contacts carried by said top in operative relation to said contact fingers, and means whereby the end play of said armature may be adjusted during manufacture and then permanently set whereby the armature may be removed and replaced without disturbing the end play and whereby need for extreme accuracy in manufacture is obviated.

3. In combination in a relay, a supporting top, an electromagnet and co-coacting armature carried by said top, a contact finger on said armature comprising a main member having a back contact and provided with a pivot point intermediate its length and a secondary front contact carrying member adapted to freely rest on and pivot about said pivot point, said secondary contact carrying member being trapped at its contact carrying end and spring pressed at its opposite end, whereby it is held in intimate contact with said pivot point, and front and back contacts carried by said top in operative relation to said fingers whereby upon energization of the relay the front contacts co-act to cause the secondary front contact carrying member to rock about the pivot point and compress the spring.

4. In combination in a relay, a supporting top, an electromagnet and coacting armature carried by said top, a contact finger on said armature, a front contact on said finger having a slot formed in the end thereof and a coacting front contact carried by said top, a back contact spring rigidly attached to said finger at one end and free to pass through the slot in the finger at the other end and having said end bent over whereby a definite spring pressure is trapped, a contact on said spring and a coacting back contact carried by said top whereby the trapped pressure of said spring may be readily modified to change the pressure on the back contacts when the relay is deenergized.

5. In combination in a relay, a supporting top, an electromagnet and coacting armature carried by said top, a contact finger on said armature comprising a main member, a pivot point on the main member and a secondary contact carrying member loosely resting thereon to be oscillatably mounted thereon, a

- spring pressed stud and spring adapted to hold said contact carrying member under trapped tension, coacting contacts carried by said top, and means whereby upon depression of said spring said stud may be rotated to vary the amount of trapped tension to modify the pressure between the coacting contacts upon energization of the relay.
6. In combination in a relay, a supporting top, an electromagnet and coacting armature carried by said top, a contact finger on said armature, a gauze contact, spring supporting means on said finger adapted to support said gauze contact, coacting contacts carried by said top, an extension on said gauze contact adapted to carry a current conducting pigtail, and a pigtail between said extension and said finger whereby current passing through the contacts will be bypassed to the finger thereby avoiding heating of the spring supporting means.
7. In combination in a relay, a supporting top, an electromagnet and coacting armature carried by said top, a contact finger insulatively mounted on said armature having both front and back contacts, a coacting back contact supported by said top, a coacting front contact and supporting means adapted to be screwed into said top and provided with a lateral extending ear adapted to engage with a recess formed in said top whereby said contact supporting means is locked against rotation.
8. In combination in a relay, a supporting top, an electromagnet and coacting armature carried by said top, fixed contacts carried by said top, a coacting contact finger of rigid cross section having a flexible rear extension, means for rigidly attaching said extension to said armature, and threaded adjusting means associated with the rigid section whereby the finger may be caused to hinge about the flexible rear extension whereby the finger may be adjusted relative to its fixed contacts.
9. In combination in a relay, a supporting top, an electromagnet and coacting armature carried by said top, fixed contacts carried by said top, a coacting contact finger of channel section having a flattened rear extension, means for rigidly attaching said extension to said armature, and threaded adjusting means associated with the rigid section whereby the finger may be caused to hinge about the flexible rear extension whereby the finger may be adjusted relative to its fixed contacts.
10. In combination in a relay, a supporting top, an electromagnet and coacting armature carried by said top, fixed contacts carried by said top, a coacting contact finger of rigid cross section having a flexible rear extension, means for rigidly attaching said extension to said armature, and an adjusting nut rotatably mounted in the rigid section in spaced relation from the flexible extension and adapted to coact with a supporting stud on said armature whereby the finger may be caused to hinge about the flexible rear extension whereby the finger may be adjusted relative to its fixed contacts.
11. In combination in a relay, a supporting top, an electromagnet and coacting armature carried by said top, fixed contacts carried by said top, a coacting contact finger of channel section having a flattened rear extension, means for rigidly attaching said extension to said armature, and an adjusting nut rotatably mounted in the channel section in advance of the flattened section and adapted to coact with a supporting stud on said armature whereby the finger may be caused to hinge about the flexible rear extension whereby the finger may be adjusted relative to its fixed contacts.
12. In combination in a relay, a supporting top, an electromagnet and coacting armature carried by said top, fixed contacts carried by said top, a coacting contact finger of rigid cross section having a flexible rear extension, means for rigidly attaching said extension to said armature, and an adjusting nut rotatably mounted in the rigid section in spaced relation from the flexible extension and adapted to coact with a supporting stud on said armature whereby the finger may be caused to hinge about the flexible rear extension whereby the finger may be adjusted relative to its fixed contacts.
13. In combination in a relay, a supporting top, an electromagnet carried by said top, a coacting armature removably supported by said top, a contact finger insulatively mounted on said armature, front and back contacts carried by said top in operative relation to said contact finger and two trunnions associated with said armature one of which is adapted to have an initial horizontal adjustment and then be permanently fixed and the other having no horizontal adjustment but being removably mounted whereby said armature may be removed from the relay without disturbing the end play adjustment.
14. In combination in a relay, a supporting top, an electromagnet carried by said top, a coacting armature removably supported by said top, a contact finger mounted on said armature, a fixed contact carried by said top in operative relation to said contact finger and trunnions for supporting said armature, one of which is headless and adapted to be adjusted horizontally during manufacture and the other being provided with a head and removably attached whereby the armature may be removed from the relay without disturbing the horizontal adjustment.
15. In combination in a relay, a supporting top, an electromagnet carried by said top, a coacting armature removably supported by said top, fixed contacts carried by said top, a coacting contact finger of rigid cross sec-

tion having a flexible rear extension, means for insulatively attaching said extension to said armature, threaded adjusting means associated with the rigid section whereby the finger may be caused to hinge about the flexible rear extension and trunnions associated with said armature one of which is adapted to have an initial horizontal adjustment and then be permanently fixed and the other having no horizontal adjustment but being removably mounted whereby the contact finger may be adjusted as to end play and vertical position in relation to its coacting contact and the armature may be readily removable without disturbing this adjustment.

16. In combination in a relay, a supporting top, an electromagnet carried by said top, downwardly depending supporting studs carried by said top, a coacting armature, means comprising a bearing plate adapted to slide vertically on said supporting studs for supporting said armature whereby it may be adjusted in relation to the permanent magnet, fixed contacts carried by said top, a coacting contact finger of rigid cross section having a flexible rear extension, means for insulatively attaching said extension to said armature, threaded adjusting means associated with the rigid section whereby the finger may be caused to hinge about the flexible rear extension and trunnions associated with said armature one of which is adapted to have an initial horizontal adjustment and then be permanently fixed and the other having no horizontal adjustment but being removably mounted whereby the contact finger may be adjusted as to end play and vertical position in relation to its coacting contact and the armature may be readily removable without disturbing this adjustment.

17. In combination in a relay, a supporting top, an electromagnet carried by said top, supporting studs carried by said top, an armature for said electromagnet, a bearing plate adapted to slide vertically on said supporting studs for supporting said armature in adjustable relation to the electromagnet, a contact finger mounted on said armature, a fixed contact carried by said top in operative relation to said contact finger, and trunnions for supporting said armature one of which is headless and adapted to be adjusted horizontally during manufacture and the other being provided with a head and removably attached whereby the armature may be removed from the relay without disturbing the horizontal adjustment.

18. In combination in a relay, a supporting top, an electromagnet and coacting armature carried by said top, an articulated contact finger carried by said armature having a main supporting member having a slot formed in the end thereof, a secondary contact carrying member pivotally mounted thereon having a contact at the end thereof, a downwardly

projecting member at the end of said secondary member having an enlarged end and adapted to project through said slot, and spring pressed means associated with the opposite end of said secondary member whereby the contact is free to be depressed upon energization of the relay but is limited in its relative vertical movement upon deenergization of the relay.

19. In combination in a relay, a supporting top, an electromagnet and coacting armature carried by said top, an articulated contact finger carried by said armature having a main supporting member having a slot formed in the end thereof, a vertical stud having a rounded end carried by said main member, a secondary contact carrying member having an indentation formed therein adapted to coact with the end of said stud to form a pivot and having a contact at the end thereof, a downwardly projecting member at the end of said secondary member having an enlarged end and adapted to project through said slot, and spring pressed means associated with the opposite end of said secondary member, whereby the contact is free to be depressed upon energization of the relay but is limited in its relative vertical movement upon deenergization of the relay.

20. In combination in a relay, a supporting top, an electromagnet and coacting armature carried by said top, an articulated contact finger carried by said armature having a main supporting member having a slot formed in the end thereof, a back contact spring rigidly attached to said finger at one end and free to pass through the slot in the finger at the other end, said end being bent over whereby a definite spring pressure is trapped, a contact on said spring and a coacting back contact carried by said top whereby the trapped pressure of said spring may be readily modified to change the pressure on the back contacts when the relay is deenergized, a secondary contact carrying member pivotally mounted thereon having a contact at the end thereof, a downwardly projecting member at the end of said secondary member having an enlarged end and adapted to project through said slot, and spring pressed means associated with the opposite end of said secondary member whereby the contact is free to be depressed upon energization of the relay but is limited in its relative vertical movement upon deenergization of the relay.

21. In combination in a relay, a supporting top, an electromagnet and coacting armature carried by said top, an articulated contact finger carried by said armature having a main supporting member having a slot formed in the end thereof, a back contact spring rigidly attached to said finger at one end and free to pass through the slot in the finger at the other end said end being bent over whereby a definite spring pressure is trapped, a con-

- tact on said spring and a coacting back contact carried by said top, whereby the trapped pressure of said spring may be readily modified to change the pressure on the back contact 5 tacts when the relay is deenergized, a vertical stud having a rounded end carried by said main member, a secondary contact carrying member having an indentation formed therein adapted to coact with the end of said 10 stud to form a pivot and having a contact at the end thereof, a downwardly projecting member at the end of said secondary member having an enlarged end and adapted to project through said slot, and spring pressed 15 means associated with the opposite end of said secondary member whereby the contact is free to be depressed upon energization of the relay but is limited in its relative vertical movement upon deenergization of the relay.
- 20 22. In combination in a relay, a supporting top, an electromagnet and coacting armature, carried by said top, a contact finger on said armature comprising a main member and a secondary contact carrying member oscillat- 25 ably mounted thereon, a spring pressed stud and spring adapted to hold said contact carrying member under trapped tension, coacting contacts carried by said top, and locking ears formed on said contact carrying member, and 30 an enlarged end on said stud adapted to engage said locking ears whereby upon depression of said spring said stud may be rotated to vary the amount of trapped tension to modify the pressure between the coacting 35 contacts upon energization of the relay. 100
23. In combination in a relay, a supporting top, an electromagnet and coacting armature, carried by said top, a contact finger on said armature comprising a main member and a secondary contact carrying member oscillat- 40 ably mounted thereon, a spring pressed stud and spring adapted to hold said contact carrying member under trapped tension, a nut adapted to engage said stud non-rotatably 45 mounted in the contact carrying member, coacting contacts carried by said top and means whereby upon depression of said spring said stud may be rotated to vary the amount of trapped tension to modify the pressure between the coacting contacts upon energization of the relay. 110
- 50 24. In combination in a relay, a supporting top, an electromagnet and coacting armature carried by said top, an articulated contact 55 finger carried by said armature having a main supporting member having a slot formed in the end thereof, a nut adapted to engage said stud non-rotatably mounted in the contact carrying member, a secondary contact carrying member pivotally mounted thereon having a contact at the end thereof, a downwardly projecting member at the end of said secondary member having an enlarged end and adapted to project through said slot, and 60 spring pressed means associated with the op- 120
- posite end of said secondary member whereby the contact is free to be depressed upon energization of the relay but is limited in its relative vertical movement upon deenergization of the relay. 70
25. In combination in a relay, a supporting top, an electromagnet carried by said top, a coacting armature removably supported by said top, a contact finger mounted on said armature, a fixed contact carried by said top in operative relation to said contact finger and trunnions for supporting said armature, one of which trunnions is adjustable horizontally during manufacture, means for fixing said one trunnion in adjusted position, the other 75 said trunnion being removably attached whereby the armature can be removed from the relay without disturbing said horizontal adjustment. 80
- In testimony whereof, I have signed my 85 name to this specification.
